(57) **CLAIM**

The ornamental design for an aircraft seat leg, as shown and described.

DESCRIPTION

FIG. 1 is a perspective view from the front side of an aircraft seat leg.

FIG. 2 is a perspective view from the rear side thereof.

FIG. 3 is a front elevation view thereof.

FIG. 4 is a rear elevation view thereof.

FIG. 5 is a top plan view thereof.

FIG. 6 is a bottom plan view thereof.

FIG. 7 is a left side elevation view thereof; and,

FIG. 8 is a right side elevation view thereof.

The broken lines shown in drawings are for the purpose of showing background structure only and form no part of the claimed design.
